ADJUSTABLE SEAT AND BACK REST CHAIR CONSTRUCTION

Orla N. Hathaway, Coral Gables, Fla., assignor to
American Airmotive Corporation, Miami, Fla.,
a corporation of Florida

Application December 13, 1950, Serial No. 290,667

3 Claims. (Cl. 155—116)

1

This invention relates to improvements in seat constructions and has particular reference to an adjustable and reclining type of seat primarily for use in aircraft.

It is an object of the present invention to provide a novel locking means whereby the seat may be quickly and easily shifted to varying degrees of adjustment and securely held against accidental movement.

The invention contemplates novel locking means that is arranged upon both sides of the seat, providing an even sliding adjustment that avoids any tendency of the seat to twist or bind upon its guides, with the locking devices being simultaneously controlled by a push button that is conveniently located upon the arm support of the seat.

The invention further contemplates a novel back support that is hinged to the seat frame to shift to varying degrees of angularity as the seat frame is shifted upon its supporting guides, with the back support being limited in its angularity by its abutting relation to the seat frame and with the hinge means being so arranged as to permit freedom of forward swinging movement of the back support whereby the back support may be swung to overlying substantial parallelism with the seat frame at such times as the seat may be bodily transferred for storage or in such instances as to permit the stacking or storing of various commodities upon the seat when the aircraft is to be employed as a cargo carrier.

It is contemplated that the novel seat construction shall be formed in either single or multiple form, with each individual seat equipped with independent button controlled locking means.

Novel features of construction and operation will be described and pointed out during the course of the following description, reference being had to the accompanying drawings, wherein has been illustrated a preferred exemplification of the invention and wherein like characters of reference are employed to denote like parts throughout the several figures.

In the drawings:

Figure 1 is a side elevation of a seat constructed in accordance with the invention, illustrating the back support in the forward folded position.

Figure 2 is a similar view with the seat adjusted to its maximum forward position and with the back support inclined to a reclining position.

Figure 3 is a fragmentary detail section of a lock controlling button carried by the seat arm,

Figure 4 is a top plan view of the seat frame and its locking means, parts broken away for sake of clearness,

Figure 5 is a side view thereof,

Figure 6 is an enlarged transverse section, taken on line 6—6 of Figure 5 and,

Figure 7 is a horizontal section through one of the seat locking elements.

Referring specifically to the drawings, the 10 numeral 5 designates a base frame, preferably formed of light weight metal tubing, such as aluminum and provided with legs 6 and 7, suitably tied together and braced by crossed tubing 8. The legs 7 are extended upwardly to form a 15 pivotal point 9, for a back support, to be described. When the seats are formed in multiple, they are rigidly connected by horizontal tubing 10, shown in section, in Figures 1 and 2. A rigid tubing 11 is arranged upon opposite sides of the device to 20 form a pivotal support 12, for locking and guiding devices, to be described. The tubing 11, for purposes of structural convenience, is angled in opposite directions from its pivotal point 12. The several tubes forming the base frame are 25 preferably welded together to form an extremely rigid support. A rigid arm rest 13 is carried at the forward end of the base frame and provides a mounting support for a push button 14 to control the seat locking devices. The arm rest 13 is 30 held against lateral movement by a rigid tubing 15, welded to the crossed tubes 8, as clearly shown. It will of course be understood, that the arm rest 13 will be suitably upholstered.

A shiftable seat frame 16, designated as a 35 whole, is adapted to be mounted within the base frame in a manner to permit forward and rearward shifting movement. The frame 16 comprises a pair of parallel spaced apart side tubes 17, rigidly connected together at their forward ends by a tube 18 and at their rear ends, by a tube 19, welded thereto. The frame 16 is adapted to support a suitably upholstered and cushioned seat, not shown, for removable mounting thereon. Each tube 17, adjacent its rear end, is provided with a generally U-shaped and rearwardly 40 inclined hinge element 20, preferably welded thereto. Each tube 17 is further provided with depending tubular lugs 21, spaced apart and identically spaced from the forward ends of the tubes. The lugs 21 rigidly support polished guide rods 22, parallel with the tubes 17 and spaced therefrom. The rods 22 slidably engage locking devices, designated as a whole by the numeral 23. 45 The locking devices 23, identically disposed upon opposite sides of the structure, comprise

generally rectangular housings 24, open upon their sides. Each housing is provided with a pair of spaced depending ears 25, apertured and having straddled engagement over the tubes 11 and pivotally supported thereon by the pivot 12. The ends of each housing is provided with integral tubular guide sleeves 26, slidably engaging the rods 22. As clearly shown, the rods pass entirely through the housings. The housings are thereby pivotally supported upon the base frame and slidably support the seat frame 16. Each housing is provided with angularly disposed apertured bearing plates 27, rotatably supporting a common rockshaft 28, transversely extending across the seat frame 16. The shaft 28 is slightly extended at one end and has fixed thereon, a vertically extending crank arm 29. The crank arm 29 at its upper end is pivotally connected to a link 30, the opposite end of which is pivotally connected at 31, to the extended end 32 of the push button 14. The push button is slidably supported in a tubular bushing 33, exteriorly threaded and rigidly supported in an opening of the arm rest 13, by suitable lock nuts 34. It will therefore be apparent, that pressure exerted upon the push button 14, will be transmitted through the link 30 to swing the crank 29 rearwardly to rock the shaft 28 in a counterclockwise direction. Adjacent each housing 24, the rockshaft 28 is provided with upstanding pins 35, apertured and threaded for the reception of laterally extending and adjustable tappet pins 36, for a purpose to be presently described.

Adjacent the side of each housing 24 and spaced from the rods 22, are a guide pin and a fulcrum pin 37 and 38. The pins 37 and 38 are vertically arranged and spaced apart, as clearly shown in Figure 7. Locking plates 39, apertured at 40, engage over each rod 22, with the aperture 40 being somewhat larger in diameter than the diameter of the rods 22 to permit the plates to both slide and rock upon the rods. One end of each plate has abutting engagement with its adjacent fulcrum pin 38, while the opposite ends of the plates are extended in opposed relation to lie in the path of movement and be contacted by the tappet pins 36. It will be apparent, that when the shaft 28 is rocked under the influence of the push button 14, the plates 39 will be shifted rearwardly. The inner ends of the plates 39 surrounding the aperture 40 may be formed relatively thick or may be equipped with preferably integral hardened lock washers 41, adapted to grip the rods 22 when the plates are angularly disposed. Means are provided to normally maintain the plates 39 in angularly disposed gripping engagement with rods 22, comprising coiled compression springs 42, arranged in the housings and surrounding the rods 22. The springs 42 at one end contact the inner end wall of the housings and at their opposite ends contact the washers 41. The springs are maintained in proper contacting relation to the washers 41 by the guide pins 37. The plates 39 in their angularly disposed gripping action contact the tappet pins 36 and maintain the push button 14 in upward position. To release the gripping action of the plates 39 in order to shift the seat frame either forwardly or rearwardly, the operator merely presses upon the button 14, causing the rockshaft 28 to rotate through the medium of the link 30 and, through contacting engagement of the tappet pins 36 with the plates 39, shifts the plates simultaneously upon their fulcrum pins 38 against the tension of the springs 42 for a release from the rods 22, permitting the

seat frame to be bodily shifted as desired. Release of the button 14, permits the springs to move the plates again to gripping locking engagement with the rods 22. The seat frame 16 is limited in its shifting movement by the abutment of the sleeves 26 with the lugs 21.

A generally rectangular back support 43 of U-shape is likewise preferably formed of metallic tubing of light weight material. The terminal ends of the U-shaped frame are formed on an identical arc, as at 44, with the terminal ends 44 normally abutting the rear ends of the seat frame side tubing 17 throughout the normal shifting movement of the seat frame. Diagonal rods or tubes 45 are welded to the frame 43, as at 46 and are maintained in their angular relation by short sections of tubing 47. The free ends of the tubes 45 are pivotally supported at 48 between the plates of the hinge elements 20. It will be apparent from the disclosure, that the rear portion of the seat frame 16 is supported from the back support 43, while the forward part of the seat frame is supported by the locking devices 23. The limit of angularity of the back support is determined by the limit of traverse of the rods 22 through the housings 24 and the maximum angularity of the back support to a reclining position is predetermined. The back support is adapted to be upholstered in any desirable manner. It will be apparent, that since the rear end of the seat frame 16 is supported from the back frame, an arcuate movement of the back frame will impart a slight rise and fall to the rear of the seat frame and to accommodate this movement, the housings 24 obviously must partake of a pivotal movement.

In the use of the device, the operator when desiring to shift the back support to a particular angularity, merely presses upon the push button 14 to release the locking devices 23 and then by shifting his weight in the proper direction, causes the seat frame and its hinged back support to move to the proper position and angularity simultaneously. Release of the push button 14 permits the springs 42 to immediately shift the plates 29 to gripping engagement with the rods 22, moving the rockshaft 28 in a clockwise direction through the medium of the tappet pins 36 and to project the push button to its extended operative position. When it is desired to fold the back support forwardly, as in Figure 1, the seat frame 16 is shifted rearwardly the maximum distance, at which point, the back support 43 can be swung downwardly to overlie the seat. In this position, the exposed surfaces of the back may be utilized for storing cargo thereon, as when the aircraft is to be employed as a cargo carrier temporarily. The base frame 5 may likewise be detachable from the floor and the unit moved bodily to one side of the craft or it may be bodily removed from the aircraft.

It will be apparent from the foregoing, that a very novel seat construction has been provided. The seat frame and its companion back support are easily and quickly shifted to varying degrees with a minimum of effort. The dual locking and guiding means assure of an even sliding movement of the seat with no tendency to twist and the control push button is arranged in a convenient location and avoids the inconvenience of reaching under the seat in order to release the seat lock as is common in seats now in use. The structure is rigid, has few and simple parts requiring a minimum of attention, may be manufactured at a relatively low cost and is highly convenient in use. The general structure, while

being shown and described as primarily formed of metallic tubing, obviously readily lends itself to other methods of construction.

It is to be understood, that the invention is not limited to the precise shape or arrangement of parts, but that various changes are contemplated as fall within the spirit of the invention or the scope of the subjoined claims.

Having described my invention, what I claim as new and desire to secure by Letters Patent is:

1. A shiftable seat device having a reclining back support connected therewith, a rigid tubular base frame provided with an arm rest, a guide device pivotally supported on the base frame at opposite sides, spring actuated locking devices carried by each guide device, a shaft extending across the base frame and journalled in the guide devices, means carried by the shaft for releasing the locking devices simultaneously, a button supported on the arm rest, connecting means between the button and the shaft for controlling the rotation of the shaft in one direction, a seat frame of rectangular shape having rear terminal ends, guide rods carried by the seat frame adapted to traverse the guide devices and controllable by the locking devices, a back supporting frame of rectangular shape having lower terminal ends adapted to abut the terminal ends of the seat frame, the back frame hingedly connected to the seat frame and adapted to be shifted to varying degrees of angularity under the influence of the shifting movement of the seat frame, the back supporting frame pivotally connected to the base frame, the pivotal and hinge connection of the back supporting frame permitting the back supporting frame to be folded forwardly and downwardly to overlie the seat frame.

2. A reclining seat structure for aircraft that has a seat frame and a back supporting frame adapted to be shifted in a manner to vary the angularity of the back supporting frame, a rigid base frame formed of metallic tubing, an arm rest rigidly carried by the base frame, guide devices pivotally supported on the base frame to rock in a vertical plane, axially aligned guide sleeves formed on the guide devices, spring actuated locking means supported in the guide devices, a rock-shaft extending transversely of the base frame and journalled in bearings carried by the guide devices, means carried by the rock-shaft to simultaneously shift the locking means to release position against the tension of the springs, a crank arm fixed upon one end of the rock-shaft, actuating means supported by the arm rest for actuating the crank in one direction, a rectangular seat frame comprising tubular parallel side members provided at their rear ends with upstanding and rearwardly inclined hinge devices, guide rods arranged beneath the side members and spaced therefrom in parallel relation, the rods travers-

ing the guide devices when the seat is shifted, the locking means adapted to engage and grip the rods for retaining the seat frame in adjusted position, said back support comprising a rectangular tubular frame having lower terminal ends formed on an arc for abutting engagement with the terminal ends of the seat frame whereby the angularity of the back support is determined by the position of adjustment of the seat frame, the back support being pivotally connected to the base frame, the seat frame being wholly supported throughout its movement by the guide devices and said hinged devices which are connected to the back support, the hinged connection and the pivotal connection of the back support to the base frame permitting the back support to be folded forwardly to overlie the seat frame.

3. The structure as recited in claim 2, wherein each of the guide devices comprise a housing open at its sides, the pivotal means for the guide device including integral ears for straddling engagement over portions of the tubular base frame, a guide pin and a fulcrum pin spanning the housing of each guide device, a locking plate for each housing that is apertured to slidably receive the guide rods, the plates fulcrumed on the fulcrum pins and extending outwardly of the housings in opposed relation, coiled springs surrounding the guide rods and bearing against the housings and the plates to shift the plates to angular gripping engagement with the rods, rigid parallel pins carried by the rockshaft, tappet devices adjustably carried by the pins in a position to engage the extended ends of the plates, the rockshaft when rotated in one direction adapted to shift the plates to a position of release from the rods through the medium of the tappets to permit the seat frame to be bodily shifted in a horizontal plane, the rockshaft and its associated elements adapted to be shifted to inoperative position upon release by the action of the springs moving the plates to locking position upon the rods.
